ABSORPTION REFRIGERATOR

Filed April 9, 1928

Inventor
Max Alex

By Fabel & Banning Atty.

UNITED STATES PATENT OFFICE.

MAX ALEX, OF BLOOMINGTON, ILLINOIS.

ABSORPTION REFRIGERATOR.

Application filed April 9, 1928. Serial No. 268,593.

My invention relates to absorption refrigerators and has for its object the provision of a device of this character which embodies some of the features outlined in my 5 prior applications, Serial No. 138,902 and Serial No. 138,903, both filed on October 1, 1926.

My present invention is designed to bring about more efficient refrigeration. One feature of my invention contemplates the provision of improved cooling facilities in the cooling chamber and elsewhere.

Another feature of my invention contemplates improved means for preventing the 10 passage of water from the generating chamber to the cooling chamber.

Another feature of my invention contemplates improved means for periodically and automatically returning to the generating 15 chamber such water as may yet pass from the generating chamber into the cooling chamber during the operation of the device.

I will explain my invention more in detail by referring to the accompanying drawing 20 illustrating rather diagrammatically one embodiment thereof.

In this drawing—

Fig. 1 represents a rather diagrammatic illustration of a refrigerator constructed in 25 accordance with my invention;

Fig. 2 is a diagrammatic view of the electrical circuit arrangements and connections;

Fig. 3 is a sectional view on line 3—3 of Fig. 1; and

Fig. 4 is a sectional view on line 4—4 of Fig. 1.

In accordance with my invention, I provide a combined generating and absorbing tank 10 which at the inception of the operation of the device is filled with a suitable mixture of ammonia gas and water so that the said tank is about three-fourths full. This tank cooperates with a cooling tank 11. This cooling tank is shown in the drawing unmounted in a refrigerating box as it is thought that the illustration of this box is not needed for purposes of clarity. I might say, however, that this cooling tank 11 has a central opening 12 into which the articles which are to be cooled or frozen may be placed. This tank 11 is mounted in any suitable form of box provided with suitable insulation and provided with suitable doors as is customary and well understood.

The generating tank 10 is provided with a suitable electric heating coil 13 merely in-

dicated diagrammatically and is also provided with a cooling coil 14 arranged preferably in a zigzag manner as shown, this cooling coil having the inlet pipe 15 and the outlet pipe 16. A thermostat 17 is also provided in connection with this generating tank 10.

In accordance with my invention, I provide a water eliminator 18 which consists of the hollow shell 19 having two walls 20 and 21 arranged therein. These walls divide the water eliminator into three compartments as will be apparent, that is, the central compartment and the two side compartments communicating one with the other through 70 ducts 22 extending through the central chamber. The central chamber has a water inlet pipe 23 and a water outlet pipe 24 so that water may circulate through the central chamber and in a measure cool the gaseous 75 evaporation from the generator 10 as they enter into the left-hand side chamber or compartment of the eliminator 18 through the pipe 25. This pipe extends from the generator 10 to the said left-hand compartment of 80 the eliminator 18 as shown. The right-hand side compartment of the eliminator 18 extends by means of two pipes 26 and 27 respectively, to the cooling tank 11 as will presently be explained.

A thermostat 28 is provided preferably in the refrigerating compartment 12 or elsewhere as the requirements may be, which thermostat is responsive to the atmosphere surrounding the articles to be cooled or 90 frozen. The cooling tank 11 has the continuity of its interior broken by an annular compartment 29 formed of the walls 30 and 31 so that but for certain passages presently to be described, this compartment 29 by value 95 of its walls forms in the tank 11 two concentric compartments, the compartment 32 and the compartment 33. These two compartments 32 and 33 are united by ducts 34 and 35 extending through the walls forming the 100 compartment 29.

The compartment 29 carries cooling water and has an inlet pipe 36 and an outlet pipe 37. A relief pipe 38 is also provided which permits the compartment 29 to drain whenever the supply of water is cut off. This relief pipe 38 permits air to enter the compartment and thus permit draining of this compartment through the outlet pipe 37.

The refrigerant conducting pipes 26 and 110 27 which start from the eliminator 18 extend into the tank 11, the pipe 26 terminating near

the bottom of the inner compartment 32 and the pipe 27 terminating near the bottom of the outer compartment 33.

From the eliminator 18, a pipe 39 extends 5 to near the bottom of the tank 10, this pipe serving two purposes as will presently appear, one of these purposes being the return of water from the eliminator 18 back to the tank 10. A pipe 40 extends from the chamber 32 10 of the tank 11 and connects with the pipe 39 at an intermediate point thereof, this pipe 40 serving to permit passage of the gaseous ammonia to be absorbed by the water in the tank 10.

15 I connect the pipe 40 to an intermediate portion of the pipe 39 in order to prevent water from flowing from the tank 10 into the tank 11. If pipe 40 extended to the bottom of the tank 10 without being connected to the 20 pipe 39, such flow of water might take place because of the differences in pressure within the tanks 10 and 11 when the heater 13 is vaporizing the ammonia. This difference of pressure is brought about because the eliminator 18 reduces the temperature of the vapor 25 in order to eliminate the water as will presently appear and this difference of pressure between the two tanks might thereupon be sufficient to expel water from the tank 10 into 30 the tank 11.

A valve 41 serves to control the flow of water from a water supply pipe 42 into the pipes 23 and 36 respectively, and a valve 43 serves to control the flow of water through the 35 pipe 15. Both of these valves are subject to the control of the thermostats 17 and 28 respectively, as will be more readily apparent from the illustration of the circuit connections as shown in Fig. 2. Whenever the circuit 40 to the controlling elements of the valves 41 and 43 is closed so that current passes therethrough, then these valves are open and water is permitted to pass; but when the electromagnetic controlled elements are not energized, these valves are closed.

The circuit diagram of Fig. 2, I believe, is 45 readily intelligible moreover as it conforms to the operation as disclosed in my said co-pending application. The walls of the compartment 29 may be provided with longitudinal fins or vanes to emphasize and enhance the cooling action of the water passing through the compartment 29. A drain pipe 44 is shown which serves to drain off the cooling 50 water from the various compartments in which it is used.

In operation let us assume that the tank 10 55 is filled to about three-fourths its capacity with ammonia gas absorbed by water, that is, a mixture of ammonia gas and water. The thermostat 28 which is so regulated as to maintain an open circuit when the chamber 12 is at its proper refrigerating temperature 60 closes circuit through its contacts which thereupon closes the circuit through the

heater 13 and also closes circuit through the valve 41. The contents of the tank 10 are thus being heated and at the same time cooling water is flowing through the compartment 29 and the central compartment of the eliminator 18. The heat generated in the tank 10 70 vaporizes the ammonia and also to a slight extent some of the water. This vapor leaves the tank 10 through the pipe 25 and enters the left-hand compartment of the eliminator 18. 75 The vapor then passes through the ducts 22 where it is partially cooled and continues on to the right-hand compartment of the eliminator 18.

The cooling of the vapor causes the water 80 to condense and to flow through the pipe 39 back into the tank 10. The ducts 22 should, of course, be slightly inclined so that the water drains to the left. The vapor as it was originally generated in the tank 10 might 85 have a temperature between the limits of 130° and 190° F. The vapor then passes through the pipes 26 and 27 into the compartments 32 and 33 respectively. The pressure in these compartments 32 and 33 of course will be 90 somewhat less than the pressure within the tank 10 because of the condensing or cooling brought about by the water eliminating step within the eliminator 18. As the vapor enters the tank 11, it is condensed into liquid 95 form due to the cooling action of the compartment 29 through which cooling water is now flowing. The heating within the tank 10 may continue until such a time as the temperature within the tank reaches 190° F. 100 Thereupon, the thermostat 17 which has been in the position shown in Fig. 2 reverses its position and closes circuit through its other two contacts, thereby breaking the circuit through the heater coil 13, and also through the valve 41 but at the same time closes the circuit through the valve 43.

The cooling water now ceases to flow 105 through the eliminator 18 and ceases to flow through the compartment 29. Cooling water now flows through the pipe coils 14 to cool the remaining contents in the tank 10 which now to a large extent is water. Thereupon, the cooled water in the tank 10 begins to absorb the ammonia which has been condensed 110 within the tank 11, and this ammonia passes upwardly through the pipe 40 to the bottom of the tank 10. The evaporation of the ammonia cools the compartment 12. This return of the ammonia to the tank 10 continues 115 until such time as the temperature within the compartment 12 is at the proper value, whereupon the thermostat 28 reverses itself from the position shown in Fig. 2 and thus opens the circuit through the valve 43 so that no cooling water flows any longer through the compartment 29. Thus the valves 41 and 43 are 120 closed and the circuit through the heater 13 is broken. Then as the temperature in the tank 10 decreases, the thermostat 17 reverses 125 130

itself into the position shown in Fig. 2 and keeps the parts in the position to perform their functions again in the same rotation as heretofore explained, which cycle of operations is again started when the thermostat 28, the circuit of which is now open, reverses its position into the position shown in Fig. 2.

It will be remembered that the relief pipe 38 permits complete draining of the compartment 29 when the additional supply of water through the pipe 36 is cut off. In the operation of the device, some water always passes in some way or other from the tank 10 to the tank 11. It is essential that this water be periodically returned to the tank 10. This is brought about by the pipe 27.

Let it be assumed that the fluid in the tank 11 when liquefied should have an upper surface which is slightly below the mouth of the duct 34 and thus slightly below the mouth 45 of the pipe 40. Now the addition of water to this supply would gradually raise this level. As soon as the level has been raised sufficiently to close the lower mouth of the duct 34 and the mouth 45, then the pressure in the tank 11 begins automatically to rise as there would be no passage of any of the contents of the tank 11 through the pipe 40 to the tank 10. The water being heavier than the ammonia, of course, settles at the bottom of the compartment 33 at the lower mouth of the pipe or tube 27. As the pressure within the tank 11 rises, this pressure will be sufficient shortly to force the water through the pipe 27 into the eliminator 18 from whence it can drain through the pipe 39 into the tank 10 until such time as the maximum upper level of the liquid in the tank 11 is below the mouth 45. Such restoration of the water to the tank 10 occurs periodically as occasion requires.

From what has been thus described, the nature of my invention will be clear as will also be apparent that many modifications may be made within the appended claims without departing from the spirit.

Having, however, thus described one of its forms, what I claim as new and desire to secure by Letters Patent is:

1. Refrigerating apparatus of the character described comprising a combined generation and absorption chamber, a refrigerating tank, means interiorly of said tank for conducting a cooling fluid therethrough whereby to cool the contents of said tank, said cooling means dividing said tank into two compartments, and passageways through said means whereby to establish communication between said compartments.

2. Refrigerating apparatus of the charac-

ter described comprising a combined generation and absorption chamber, a refrigerating tank, means interiorly of said tank for conducting a cooling fluid therethrough whereby to cool the contents of said tank, said cooling means dividing said tank into two compartments, one surrounding the other, and passageways through said means whereby to establish communication between said compartments.

3. Refrigerating apparatus of the character described comprising a combined generation and absorption chamber, a refrigerating tank, means interiorly of said tank for conducting a cooling fluid therethrough whereby to cool the contents of said tank, said cooling means dividing said tank into two compartments, passageways through said means whereby to establish communication between said compartments and a relief pipe associated with said means to permit draining thereof upon cessation of the passage therethrough of cooling fluid.

4. Refrigerating apparatus of the character described comprising a combined generator and absorber, a combined condenser and evaporator, a water eliminator interposed between said two devices, a drain tube leading from said eliminator into said generator-absorber, and a passageway leading from said condenser-evaporator to an intermediate point of said tube for the purpose of conducting the refrigerant to be absorbed from said condenser-evaporator to said generator-absorber.

5. Refrigerating apparatus of the character described comprising a combined generator-absorber, a combined condenser-evaporator, a passageway leading from said condenser-evaporator to a point near the bottom of said generator-absorber to permit of the absorption of refrigerant by the water within said generator-absorber, a passageway for conducting generated vapor from said generator-absorber to said condenser-evaporator, means in said last aforesaid passageway for decreasing the temperature of said vapor in its travel through said passageway, and means for preventing the flow of water from said generator-absorber through said first aforesaid passageway to said condenser-evaporator, said last aforesaid means comprising a duct extending from said second aforesaid passageway to said temperature decreasing means.

In witness whereof, I hereunto subscribe my name this 29th day of February, A. D. 1928.

MAX ALEX.
